2 Claims. (Cl. 62—314)

(Granted under Title 35, U.S. Code (1952), sec. 266)

The invention described herein may be manufactured and used by or for the United States Government for governmental purposes without payment to us of any royalty thereon.

The present invention relates generally to cooling systems for electric motors and generators and, as illustrated herein, relates more particularly to systems for cooling such machines by means of a vaporized liquid introduced into a cooling medium such as air.

The cooling of electric motors and generators has heretofore been accomplished by use of any one of three methods. The use of a stream of air passing through the machine is most generally used but is objectionable since air cooling requires the use of a large volume of air which necessitates the use of expensive fan or blower equipment. The use of water supplied in the form of spray to the interior of the machine is used to some extent but this method is difficult to control since even a small excess of water may cause short circuits with consequent damage to the machine. The use of refrigerated passages of heat exchanging tubes within the machine effectively cools the machine but involves considerable expense in installation and maintenance.

The present invention contemplates the use of air cooling in conjunction with vaporized water to provide an effective coolant which does not require immense volumes of air and which is simple to control and which effectively eliminates, nearly entirely, the danger of damage to the machine. To this end, the system provides means for supplying a column of air and means for introducing a predetermined quantity of water vapor into said column of air before it enters the machine. As illustrated, the system is so designed and controlled, that an excess of free air is removed from the column before the air enters the machine, thus effectively preventing water from collecting on the interior of the machine.

The present invention presents many advantages over prior cooling systems and methods of cooling electrical machines. The use of a column of air saturated with water vapor increases substantially the cooling effect of the column of cooling air due to the latent heat of vaporization of water. Even though the water in the column is not entirely vaporized there will, under normal conditions, be no precipitation of moisture on the interior parts of the motor or generator. Danger from such a source is effectively eliminated by the moisture trap in the duct of the cooling system. Since a much smaller volume of air is necessary to provide adequate cooling, the pump or blower mechanism is reduced to a minimum size with a consequent drop in cost. Since the air is saturated with water vapor, dust which may be drawn into the system is removed to a large extent by the moisture trap.

Another object of the invention is to improve generally upon the construction and operation of cooling systems for electric motors and generators.

With the above and other objects and features in

2

view, the invention will now be described with particular reference to a preferred embodiment thereof shown in the accompanying drawings and in which:

Fig. 1 is a view in front elevation of a preferred embodiment of the present invention;

Fig. 2 is a view in side elevation of the construction shown in Fig. 1;

Fig. 3 is a view partly in section, of a shutter for controlling the flow of air to a fan or blower;

Fig. 4 is a view in section taken along the line IV—IV of Fig. 3; and

Fig. 5 is a view, partly in section, of a portion of the air duct having therein vaporizing means.

The present invention is illustrated as applied to a generator test stand to provide cool air for generators undergoing test. It is clear, however, that the present invention is not limited to such use but may be used to cool electric motors or generators in actual use at locations where high ambient temperatures are found.

The generator test stand shown in the drawings comprises a test stand 10, only a fragmentary portion of which is shown in Fig. 1. The test stand 10 is provided with suitable power means (not shown) for supplying power to a shaft 12 which may be coupled to the shaft of a generator 14 by suitable connecting means (not shown). The generator 14 is provided with an enclosing housing 16 in which the heat developing members are enclosed. These heat developing members include the rotor and stator of the usual type of electric motor or generator. A power-driven blower 18 delivers cooling air to the housing 16 through a duct 20. Preferably the air is filtered prior to entering the blower 18. As shown in Fig. 2, air is drawn through a conventional type of air filter 22 and through an intake duct 24 into the blower 18.

The flow of air into the blower 18 is controlled by a manually operated valve 26 having a cylindrical segment 28 pivotally mounted in the valve body 26 and having an external handle 30 for rotating the segment 28 into and out of duct closing position. It is to be noted that the valve 26 is provided with an opening 32 which may be closed as the intake opening 34 in the duct 24 is being opened by rotation of the segment 28 in a clockwise direction. Thus the flow of filtered air may be increased or diminished as required. During replacement, removal of a generator or motor 14 or the flow of air to the exhaust end 36 of the valve body 26 may be prevented by rotating the segment 28 in a clockwise direction. Thus, the flow of air into the housing 16 may be delayed until after the generator or motor 14 has readied normal operating temperature. This is important for reasons which will later become apparent.

The air passes from the blower 18 and into one end of the duct 20 which is provided with a control valve 38 of conventional design which controls the flow of air into the duct 20. The filtered air from the blower 18 is relatively dry and hence must be provided with sufficient moisture to provide a substantially saturated stream of air. To this end, a vaporizer 40 is provided which supplies vaporized water to the moving air column in the duct 20. The vaporizer 40 is generally of conventional construction and comprises a water conducting tube 42 which is supplied with water from a suitable tank 44 through a flexible tube 46. For convenience, the tank 44 is secured to an upright portion of the air blast duct or conduit 20. Water may be supplied to the tank 44 through a tube 48 from a suitable source of supply and the flow of water to the tank 44 may be controlled by any suitable means such as a conventional valve controlled by a float within the tank.

The vaporizer 40 is also provided with a tube 50 which is connected to a suitable source of compressed air. As

shown in Fig. 5, the water tube 42 and the air tube 50 are assembled so that a stream of air from the tube 50 passes across the end of the tube 42 and sets up a partial vacuum therein. Water flows from the end of the tube 42 and is vaporized by the air blast from the tube 50. The stream of air passing through the duct 20 from the blower 18 mixes with the vaporized water so that the blast of air in the duct 20 is substantially saturated with moisture to produce the maximum air cooling effect. The flow of compressed air through the tube 50 may be controlled by a conventional valve 52. By controlling the flow of air through the tube 50, the flow of water through the tube 42 is also controlled. Thus, an amount of water sufficient only to substantially saturate the stream of air in the duct 20 is permitted to flow from the tube 42.

In the event, however, that too great a volume of water vapor is fed into the duct 20 so that vapor condenses, a trap 54 is provided. The trap 54 is interposed between one end of the duct 20 and the generator housing 16. The trap 54 is provided with a dish-like plate 56 in line with the entrance to the interior of the housing 16 and axially spaced therefrom. The air impinges on the plate 56 and moisture is trapped and collects in drops thereon. Moisture leaves the lower portion of the plate 56 into the lower portion of the trap 54 where it is passed through tubes 58 to a suitable waste line 60. By this means liquid is not permitted to reach the interior of the housing 16, thus serving to prevent corrosion and also short circuits.

In order to insure efficient operation, pressure of the stream of air flowing through the duct 20 is measured by readings in a manometer 62 which is fixed in a convenient location on a vertical portion of the duct 20. Pressure is measured at a point just in front of the entrance to the housing 16 in the duct 68. A suitable tube 64 extends into the passage and is connected to the manometer 62 by a flexible tube 66.

In operation, air from the blower 18, enters the duct 20 and air pressure within the duct 20 is controlled by the valve 38 according to readings recorded on the manometer 62. The compressed air valve 52 is opened to about three-fourths of its maximum which permits the desired blast of air to pass across the end of the tube 42 which causes water to be siphoned from the tank 44 and to be atomized as the water leaves the end of the tube 42. The atomized water mixes with the blast of air in the duct 20 coming from blower 18: this increases the humidity of the air and also decreases its temperature to the dry bulb temperature in proportion to its relative humidity. The humid air continues through the duct 20 and impinges against the plate dish 56 in the water trap 54. The plate dish 56 traps any condensed vapor which is drained off through the tubes 58. The humidified air then passes into the enclosing casing 16 through tube 64 on which a suitable thermometer 70 is mounted. At this point, the air blast will have

reached its lowest temperature, as indicated by the thermometer 70. The air valve 52 is gradually closed until the temperature as indicated by the thermometer 70 begins to rise: this will be the temperature of the cooling air entering the generator housing 16.

The above described apparatus and method of controlling both the amount of water vapor and the temperature of the humidified air provides an effective apparatus and method for cooling electrical apparatus of the type described above. The air blast as it enters the interior of the generator 14 is free from condensed moisture and since the temperature within the generator is relatively high there can be no accumulation of condensed moisture which might cause short circuits. Furthermore, the flow of humidified air to the interior of the generator 14 is so controlled by the valve 38 that flow of air into the duct 20 is effectively prevented until the temperature of the generator 14 on the test stand 10 has had an opportunity to reach operating temperature.

20 While the present invention has been described with particular reference to one preferred embodiment thereof, it is to be understood that the invention is not limited thereto but may be varied within the scope and spirit of the appended claims.

25 Having thus described our invention, what we claim as new and desire to secure by Letters Patent of the United States is:

1. In combination an electrical apparatus having a casing and an electrical current carrying, heat developing member and a cooling means therefor, said cooling means comprising an air filter, a blower having its inlet connected with said filter, conduit means from the outlet of said blower to said casing, valve means at the outlet of said blower, means within said conduit and downstream of said valve means for supplying water vapor to the air traveling through said conduit from said blower, and means within said conduit and downstream of said means for supplying water vapor for trapping and removing water condensed from the air prior to the entrance of the air into said casing.

2. The combination of claim 1 wherein said electrical apparatus comprises a rotor and a stator and wherein said valve means controls the pressure and velocity of said air.
